(57) **CLAIM**

The ornamental design for a solar device with removable cassette, as shown and described.

DESCRIPTION

FIG. 1 is a perspective view taken from a front, top side of a solar device with removable cassette showing my new design, with the handle/stand in a first position;

FIG. 2 is a perspective view taken from a front, bottom side of the solar device with removable cassette shown in FIG. 1;

FIG. 3 is a front view of the solar device with removable cassette shown in FIG. 1;

FIG. 4 is a back view of the solar device with removable cassette shown in FIG. 1, and illustrates the removable cassette shown in an engaged position;

FIG. 5 is a first side view of the solar device with removable cassette shown in FIG. 1;

FIG. 6 is a second side view of the solar device with removable cassette shown in FIG. 1;

FIG. 7 is a top view of the solar device with removable cassette shown in FIG. 1;

FIG. 8 is a bottom view of the solar device with removable cassette shown in FIG. 1, and illustrates the removable cassette in the engaged position;

FIG. 9 is a front perspective view taken from the bottom of the solar device with removable cassette shown in FIG. 1, and illustrates the removable cassette in a disengaged position;

FIG. 10 is a back perspective view taken from the bottom of the solar device with removable cassette shown in FIG. 1, and illustrates the removable cassette in the disengaged position;

FIG. 11 is a front perspective view taken from the top of the solar device with removable cassette shown in FIG. 1, with the handle/stand in a second position.

The broken lines shown represent unclaimed subject matter and form no part of the claimed design.

1 Claim, 9 Drawing Sheets
